United States Patent Office.

JOHN E. DOWNS, OF LOWELL, MASSACHUSETTS.

Letters Patent No. 82,392, dated September 22, 1868.

IMPROVEMENT IN SASH-FASTENERS.

The Schedule referred to in these Letters Patent and making part of the same.

TO ALL WHOM IT MAY CONCERN:

Be it known that I, JOHN E. DOWNS, of Lowell, in the county of Middlesex, and State of Massachusetts, have invented new and useful Improvements in Combination Hinge and Fastener for Blinds; and I do hereby declare that the following is a full and exact description thereof, reference being had to the accompanying drawings, and to the letters of reference marked thereon.

The nature of my invention consists in so forming and combining a hinge and fastener that it will give the required strength and support to a blind, and also to secure the same in its desired location.

To enable others skilled in the art to make and use my invention, I will proceed to describe its construction and operation.

Figure 1 represents a front elevation of a window-casement, with blinds hung and provided with my improved combination hinge and fastener.

Figure 2 represents a plan of the inside-of casement, showing the fastener.

Figures 3 and 4 are details of the combination hinge and fastener.

Similar letters in the different figures indicate corresponding parts.

a represents the casement, *b* the sill of the window. Near the top and bottom, and on each side of the casement *a*, and secured to the same, is the male portion of the hinge *c*, which is supplied with the required pintle and a suitable flange, with countersunk holes, for the reception of the requisite screws to fasten the same as required.

I construct the female part of the hinges, both for the top and bottom of the blind, with suitable sockets, *d*, to receive the pintles; the length of the leaves *e* and *f* corresponding with the width of the blinds, the leaves of the top hinges, *e e*, projecting downward on both stiles, *g* and *h*, so as to receive one or more screws; the leaves of the bottom hinges, *ff*, projecting upward on both stiles, *g* and *h*, sufficiently to receive the required number of screws; the length of these leaves, *e e* and *ff*, being determined by the width and weight of the blind, projecting across the entire width of the blind, or less, as may be desired.

To the bottom leaves of the hinges *ff*, the projections *i i* are cast on or secured to the same, as represented in fig. 4 of the drawings, by dotted lines, they being furnished with the bushings *j j*, their length being the thickness of the bottom part of the blind, on the end of which the fastener, *k*, is secured, by means of a screw. This fastener *k* is provided with the slats *ll*, through which the screw *m* passes, forming a guide for the same.

The window-sill *b* is provided with suitable catches, *n n*, driven into the same vertically, inclining outward. Similar catches are used and driven into the wall of the house, horizontally with these catches *n n*. The heels *o o*, of the fasteners *k k*, fasten the blind on the inside when closed, and to the walls of the house when open, being of themselves self-operating.

Ordinarily, in common blinds, their construction is such, the tenons of the slats being so short and shallow, that it affords but very little strength to the blind, and is scarcely, if any, prevention to the sag of the same. And further, the usual short leaves of the hinges are entirely inadequate to support the weight of the blind, they also being exposed to extreme wet, dry weather, and winds. These several causes tend and result in the sag of the blind, causing the slats to become loose, preventing the blinds from being closed, or fastened back when open, making them unserviceable and unfit for use, and oftentimes entirely destroying them.

These common and serious difficulties are entirely obviated in the construction and arrangement of my improved combination hinge and fastener.

The female part *e e* and *ff*, being applicable to the male part of old hinges now used, and can be easily attached to the same.

The leaves *e e* and *ff*, of the female part of the hinges, are supplied with a suitable rib, to give them the required strength, their length being the width of the blind, if desired, and of suitable width to receive a sufficient number of screws, which fasten it firmly to the bottom, top, and stiles *g* and *h* of the blind.

This construction and application of the leaves *e e* and *ff* to the blinds, give increased firmness, strength,

support, and durability to the same, so much so that neither wind nor weather affects them, and consequently they are always in perfect working order; and also, this arrangement being in combination with the fastener, they are always reliable to shut and fasten, and fasten when open.

What I claim as my invention, and desire to secure by Letters Patent, is—

The combination and arrangement of the hinge *e f*, and fastener *k*, when arranged for the purposes as described and fully set forth.

JOHN E. DOWNS.
